GLASS RETAINERIrving M. Footlik, Chicago, Ill., assignor to Leo
G. Pilot, Chicago, Ill.

Application April 24, 1939, Serial No. 84,516

Term of patent 14 years

To all whom it may concern:

Be it known that I, Irving M. Footlik, a citizen of the United States, residing at Chicago, Illinois, have invented a new, original, and ornamental Design for a Combined Ashtray and Glass Retainer, of which the following is a specification, reference being had to the accompanying drawing, forming part thereof.

Figure 1 is a top plan view of the combined ashtray and glass retainer showing my new design.

Figure 2 is a side elevation thereof.

Figure 3 is a sectional view along line 3—3 of Figure 1.

Figure 4 is an end elevation from the ash-tray end portion.

I claim:

The ornamental design for a combined ashtray and glass retainer, as shown.

IRVING M. FOOTLIK.
